UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

HOPPER-CAR.

1,071,699.

Specification of Letters Patent.

Patented Sept. 2, 1913.

Application filed December 20, 1912. Serial No. 737,784.

To all whom it may concern:

Be it known that I, ARGYLE CAMPBELL, a citizen of the United States, residing in Chicago, in the county of Cook and State of Illinois, have invented a new and useful Improvement in Hopper-Cars, of which the following is a specification.

This invention relates to improvements in hopper cars, and more particularly to the 10 operating mechanism for the hopper doors thereof.

One object of the invention is to provide a hopper car of a simple, strong, efficient and durable construction, provided with operating shafts which are common to several sets of hopper doors and adapted to operate the latter simultaneously.

Another object of the invention is to provide an operating mechanism for the hopper doors, of few parts and minimum number of shafts, to thereby decrease the cost of construction and save time in opening, and closing the doors.

Other and more specific objects of the invention are: to arrange the transversely extending operating shafts in such a way that it is unnecessary to cut the center sills, which would thereby be weakened; to so dispose the operating shafts that the same 30 are below and exterior to the hoppers; to provide space between some of the sets of hoppers for cross ties, and to provide novel means for adjusting the length of the connections between the hopper doors and the 35 winding drums of the door operating mechanism.

The invention furthermore consists in the improvements in the parts and devices, and in the novel combinations of parts and devices herein shown, described or claimed.

In the drawing forming a part of this specification, Figure 1 is a top plan view of half of a hopper car having my improvements embodied therein. Fig. 2 is a longitudinal, vertical section of the structure shown in Fig. 1 and taken substantially on the line 2—2 thereof. Fig. 3 is a transverse, vertical section, taken on the line 3—3 of Fig. 1. Fig. 4 is a detail, vertical sectional view, upon an enlarged scale, showing parts of the door operating mechanism. Fig. 5 is a transverse, detail, sectional view taken substantially on line 5—5 of Fig. 4 and showing parts of the operating

mechanism, and Fig. 6 is a detail sectional view, taken substantially on the line 6—6 of Fig. 5.

In said drawing, my improvements are shown as applied to a hopper car of the type generally known as the seventy ton, flat bottom hopper car which, as usually constructed, is provided with twelve hoppers arranged transversely of the car with six hoppers on each side of the center sill, but, as will be understood, the improvements are susceptible of use on other types of hopper cars.

The car body is designated generally by the reference A, and as shown is provided with a plurality of transversely extending hoppers B, said hoppers B being arranged in sets of four. The drawings in Figs. 1 and 2 illustrate approximately a half of a car, said car being provided with twelve hoppers, arranged in three sets of four each, 75 that is, each set comprises two adjacent hoppers on each side of the center sill. The hoppers in each set are divided by vertically extending partitions 10 and the adjacent hoppers of two sets are divided by 80 partitions 100. Each hopper B has the bottom thereof formed by means of a pair of hinged, oppositely swinging hopper doors 11, said hopper doors, when in closed position, forming what may be termed a substantially flat bottom, as contradistinguished from hoppers of the V shaped type. The doors of each set of four hoppers are operated simultaneously by similar mechanism, and I shall only describe the mechanism for operating the doors of one set. 85 This mechanism, as shown, comprises a common, transversely extending operating shaft 12, mounted in suitable depending brackets 13 at the center of the car, secured 90 to the bottoms of the center sills 14 and supported at its outer end by suitable depending brackets 15. Secured to said shaft 12, intermediate the brackets 13, are a pair of winding pulleys 16, to each of which is secured a chain 17, said chains being adapted 95 to wind upon said pulleys, as will be obvious, and being extended in opposite directions (see Fig. 4), and secured to pulleys 18, each of said pulleys 18 being mounted on a 100 short shaft 19, rotatably mounted in suitable bearings 20 secured to the inner sides of 105 the center sills 14. Each of said shafts 19 is

also provided with a polygonal drum 21, having an offset lug 22 and a locking face 23.

To each lug 22 is pivotally secured, on opposite sides thereof, a pair of triangular shaped plates 24, the latter having pivotally connected thereto, between the same at their outer ends, a hook shaped link 25, bifurcated at its lower end, as at 26, and having detachably, pivotally mounted within said bifurcations, an eye-bolt 27, adjustably mounted in a threaded, diamond shaped block 28, more particularly described herein-after. Also pivotally secured to said triangular shaped plates 24, and on the outsides thereof, are a pair of hook shaped links 29, the latter having detachably, pivotally mounted therebetween at their lower ends, another eye-bolt 27.

Each threaded block 28 is mounted between offset portions 30 of transversely extending channel irons 31, which are secured to the under faces of the hinged hopper doors 11, said channels, as will be understood, being adapted to operate the hopper doors on each side of the center sill in pairs simultaneously, and the block 28 being located centrally of the car beneath the center sills. Each eye-bolt 27, as above described, is detachably pivoted to the ends of the hook shaped links, as by means of a removable pin 32, and by removing said pin 32, the eye-bolt may be adjusted within the block 28. It will also be noted that each eye-bolt 27 is provided with a longitudinally extending slot 33, through which is adapted to pass a cotter pin 34, the latter being used so as to properly retain the eye-bolt in position within the block 28, and thereby prevent twisting of the connections between the doors and the winding drums. It will also be noted that the block 28 is of substantially the same height as the channel irons 31, and that therefore the adjustment between the eye-bolt and the block is accomplished without extending the eye-bolt beyond the parts of the door. Each triangular shaped plate 24 is provided with a flat bottom face 35, which co-operates with the locking face 23 of the polygonal drum, the latter being also provided with lugs 36 on the outsides of the triangular members 24, on which rest the hook ends of the links 29. The pivotal connections of the hook shaped links are so arranged that lines passing through the centers of the pivotal connections, when the doors are in closed position, will be to one side of the center of rotation of the polygonal drums, so that the load on the doors will have no tendency to release or unlock the operating mechanism.

From Fig. 2 of the drawing, it will be seen that the partitions 100 between the adjacent hoppers of two sets of hoppers are somewhat shorter than those referenced 10

above the operating shafts. This arrangement is made so that space is provided for cross-ties 37, secured to the bottoms of the center sills and to the bottoms of the intermediate partitions 100 and the various hopper sheets to thereby provide increased strength for the car.

From the foregoing description, it will be seen that I have provided a construction wherein only three operating shafts are required to open and close twelve pairs of hopper doors, whereas, so far as I am aware, it has generally been customary to provide an operating shaft for each pair of transversely arranged hoppers. It will also be noted that the operating mechanism is so arranged that the center sills are not cut away, since the short shafts supporting the polygonal drums and pulleys are mounted between the same, and that the operating shafts themselves are entirely exterior to the hoppers, and thus are not likely to become injured by the material of the load.

Although I have herein shown and described what I now consider the preferred embodiment of my invention, yet I would have it understood that the same is merely illustrative, and that all changes and modifications are contemplated as come within the scope of the claims appended hereto.

I claim:—

1. A hopper car comprising, in combination: a car body having a pair of transversely arranged, substantially flat bottom hoppers located on the same side of the center sill, the bottoms of the hoppers being formed by hinged hopper doors; a common, transversely disposed, operating shaft located intermediate said hoppers; and devices for opening and closing the doors of said hoppers simultaneously and operated from said shaft, said devices including winding drums, connections from the doors of each hopper to the winding drums, and means between said shaft and each of the winding drums for rotating the latter, substantially as specified.

2. A hopper car comprising, in combination: a car body provided with a pair of transversely arranged hoppers located on the same side of the center sill, the bottom of each hopper being formed by a pair of oppositely swinging, hinged hopper doors which are substantially horizontal when in closed position, a common, transversely disposed operating shaft located intermediate said hoppers and below the center sill; and devices for opening and closing the doors of said hoppers simultaneously and operated from said shaft, substantially as specified.

3. A hopper car comprising, in combination: a car body provided with a pair of transversely arranged, substantially flat bottom hoppers located on the same side of the center sill, the bottoms of the hoppers

being formed by hinged hopper doors; a common, transversely disposed operating shaft located intermediate said hoppers and below the center sill; and devices for opening and closing the doors of said hoppers simultaneously and operated from said shaft, said devices including a pair of winding drums, one for each of said hoppers, connections from the doors of each hopper to said winding drums, and means between said shaft and each of the winding drums for rotating the latter, substantially as specified.

4. A hopper car comprising, in combination; a car body provided with a set of hoppers, said set comprising four transversely arranged hoppers, two on each side of the center sill, and each hopper being provided with a hinged hopper door; a transversely arranged operating shaft common to all the hoppers of said set; and devices for opening and closing all the doors of said hoppers simultaneously and operated from said shaft, said devices including a pair of winding drums located centrally of the car and in the line of the center sill, connections from the doors of each pair of hoppers to the winding drums, and flexible means between said shaft and said drums for rotating the latter, substantially as specified.

5. A hopper car comprising, in combination: a car body having two sets of hoppers, each set comprising four transversely arranged hoppers, two on each side of the center sill, and each hopper being provided with a hinged hopper door; mechanism for opening and closing said hopper doors, said

mechanism including operating shafts, one for each set of hoppers; and a cross tie secured to the center sill and to the hoppers 40 and located intermediate the adjacent hoppers of the two sets of hoppers, substantially as specified.

6. A hopper car comprising, in combination: a car body having a hopper, said hopper being provided with hinged hopper doors; bars secured to said hopper doors; and mechanism for operating said doors, including an operating shaft, flexible connections, and means for adjusting the 50 length of said connections, said means including a threaded block permanently secured to said bars and a detachably pivoted eye-bolt adjustably mounted in said block, substantially as specified. 55

7. A hopper car comprising, in combination: a car body having hoppers, each hopper being provided with hinged hopper doors; transversely extending channels secured to said hinged doors and adapted to 60 operate the latter; and mechanism for opening and closing said doors, including an operating shaft, flexible connections and means for adjusting the length of said connections, said means including a threaded 65 block rigidly mounted on said channels and an eye-bolt detachably pivoted to said connections and adjustably mounted in said block, substantially as specified.
